TYPEWRITER ACCESSORY

Woodward Baldwin Rich, Baltimore, Md.

Application July 15, 1939, Serial No. 284,772

2 Claims. (Cl. 197—189)

The present invention relates in general to typewriters and more specifically to an accessory for a typewriter that will indicate to the operator the number of lines to be written, or the number of lines remaining on the page, and which will signal the operator when the requisite number of lines has been written.

An important object of my invention is to provide an indicating device synchronized with the platen roll of a typewriter so as to indicate the position on the page.

A further object of my invention is to provide an accessory for a typewriter that can be readily attached to any make of typewriter without altering materially the structural details of the typewriter.

Another object of my invention is to provide an accessory for a typewriter that can be easily and readily associated with the platen roll to designate the number of lines to be written, or the number of lines remaining on the page.

Yet another object of my invention is to provide an accessory for a typewriter that will indicate clearly to the operator the number of lines to be written or the number of lines remaining on the page to be written, which accessory consists of relatively few essential working parts, and which can be easily and cheaply manufactured.

And yet another object of my invention is to provide a typewriter accessory of the type hereinabove described which will prevent foreign matter, such as, for instance, dirt or dust, from entering the working parts, and thereby damaging such parts.

With the above and other important objects in view which will hereinafter become more fully apparent, my invention consists in the parts and combinations to be later more fully described and claimed, it being distinctly understood however that the structural details set forth herein are merely for the purpose of illustration.

In the drawing in which like numerals designate the same or similar parts:

Figure 1 is a fragmental front elevational view illustrating my novel typewriter accessory in association with the platen roll of a typewriter.

Figure 2 is a vertical sectional view taken through the accessory looking in the direction of the turning knob.

Figure 3 is a view taken along the line 3—3 of Figure 2 looking in the direction of the arrows.

Figure 4 is a sectional view similar to Figure 3 showing the working parts in inoperative position.

Figure 5 is a fragmental sectional view showing the details of the idler pinion gears.

Referring now to the drawing and more particularly to Figure 1, there is illustrated a platen roll 1 journaled in a portion of the carriage of a typewriter 2. My novel attachment device 3 and a turning knob 4 for the platen roll 1 are mounted on the shaft 5 of the platen roll.

The device 3 includes a backing plate 6 having a concentric integral hub 7 which forms a bearing for the platen shaft 5 and provides means for attaching the backing plate to the carriage 2. An additional attaching means such as a bolt 8 provided with a spacer bushing 9 is provided to prevent rotation of the plate 6.

In Figures 3 and 4 it will be noted that a drum 11 of such diameter as to rotate around the plate 6 and which is also adapted to slide relative to the plate 6 is provided, and a cover plate 12 is positioned at the open end of the drum, and affixed thereto in any desirable manner. Manifestly, the backing plate 6, the drum 11, and the cover plate 12 form the housing of my accessory device 3.

As clearly shown in Figure 4, the cover plate 12 is formed with a concentric integral hub 13 which affords an outer bearing for the platen shaft 5.

Referring again to Figure 1, it is readily apparent that the outer face of the drum 11 is provided with indicia which in this particular case consist of graduations 14 that indicate the number of lines to be written or the number of lines remaining to be written on a given page. Affixed to the outer face of the backing plate 6 is a pointer 15, the purpose of which is believed readily apparent.

Integrally formed on the inner face of the backing plate 6 is a ring gear 16 (see Figures 3 and 4) which meshes with an idler pinion 17 rotatably mounted on a pin 18. As shown in Figure 5, the pin 18 is conveniently attached to the cover plate 12. The hub of the pinion is flanged as designated at 19, and a washer 20 in spaced relation to the flanged member 19 is provided. One end of a spiral spring 21 is attached by an anchor pin 22 between the flange 19 and the washer 20, and the opposite end is attached to the hub 13 as shown at 23.

A driving pinion 24 rigidly attached to the shaft 5 is adapted to mesh in operative position (see Figure 3) with the idler pinion 17 and thereby impart rotary movement of the platen shaft 5 to the drum 11. A coil spring 25 is positioned around the platen shaft 5 between the hub 13 and

the pinion 24 to force normally the pinion 17 out of mesh with the pinion 24 or hold these gears in inoperative position.

Pivots mounted on the inner face of the plate 6 is a detent 26 which is adapted to travel in a groove 27 formed in the inner periphery of the drum 11. A leaf spring 28 is attached at one end to the ring gear 16, and the free end contacts the detent 26 to maintain the working face of the detent in the groove 27.

A cam surface 29 is located in the groove 27 as shown in Figure 2, and is so formed that the rise of the cam is virtually flush with the inner periphery of the drum 11.

A friction member designated generally 30 consisting of a substantially annular spring element 31 is retained in a groove 32 provided in the outer periphery of the ring gear 16. One end of the member 31 extends tangentially from the groove as shown at 33 and is bent outwardly at right angles as at 34 and downwardly at right angles as indicated at 35. The portion 35 is engaged in a lateral groove 36 formed in a stop member 37. The stop member 37 is integrally formed on the inner face of the drum 11 and comprises an inclined rise 38 that extends from the inner face of the drum 11 to the lateral groove 36. The opposite side of the groove 36 extends radially inward to form a stop for the friction member. In Figures 3 and 4 it can be seen that the portion forming the inclined rise is narrower than that portion forming the stop which leaves a space designated 39.

The operation of my invention may be briefly described as follows. The pointer 15 is set to indicate the desired number of lines to be written, and this is accomplished by rotating the drum 11. This rotary movement of the drum 11 will move the cam surface 29 relative to the detent 26 and the friction member 31 being in engagement with the backing plate 6 and the drum 11 will hold the parts in the desired position. The drum 11 is then moved to the right to the position shown in Figure 3 where the idler pinion 17 will mesh with the driving pinion 34. The detent 26 then drops into the groove 27 to hold the parts in the position shown in Figure 3. Simultaneously the portion 35 of the friction member 31 will move to the free space 39 as clearly shown in Figure 3. Each time the platen roll is moved, the gears 16, 17 and 24 will, when the platen shaft is rotated, transmit rotary movement to the drum 11. In addition, the rotary movement of the drum will wind the coil spring 21. When the number of lines selected to be written has been written, the cam 29 engages the detent 26 and forces it out of the groove 27. The helical spring 25 will then move the drum 11 and its integral parts to the position shown in Figure 4 thus disengaging the gears 24 and 17. However, the idler gear 17 remains in mesh with the ring gear 16. The spring 21 will then reverse the direction of movement of the drum 11 through gears 17 and 16 and the end 35 of the friction member will ride over the portion 38 of the stop 37 until it reaches the groove 36 at which position it will arrest movement of the drum 11. In other words, when the required number of lines have been written on a given page, my device will automatically return the drum to a neutral position. The term "neutral position" means the position originally selected by the operator, and in this position the operator is entirely free to rotate the platen in any direction without affecting the selected setting.

It is believed to be readily apparent from the above description that I have provided an accessory for a typewriter which can be easily and inexpensively manufactured and which can be used in conjunction with all types of typewriters on the market without necessitating any material alteration of the typewriter. In addition, the device will clearly and accurately indicate the number of lines to be written, or the number of lines remaining on the page to be written. Furthermore, with my device as soon as the predetermined number of lines have been written, the device will automatically return to its original position. It consists of few principal working parts and in the event of damage, the device can be repaired quickly and with little or no trouble.

While I have shown and described the preferred embodiment of my invention, I wish it to be understood that I do not confine myself to the precise details of construction herein set forth by way of illustration, as it is apparent that many changes and variations may be made therein, by those skilled in the art, without departing from the spirit of the invention, or exceeding the scope of the appended claims.

I claim:

1. In a typewriter having a carriage, a rotatable shaft on the carriage, a platen carried by said shaft, and a turning member for the platen, a device for indicating the number of lines to be written on a page comprising a casing having a backing plate secured to the carriage, a drum rotatable around and slidable with respect to said plate, a cover plate secured to the open end of the drum, a ring gear mounted on the backing plate, a driving gear carried by the platen shaft, an idler gear attached to the cover plate and normally out of mesh with the driving gear, the idler gear being in mesh with the ring gear, and the said idler gear being adapted to be moved into engagement with the driving gear by sliding the drum over the backing plate whereby rotary movement is imparted to the drum when the platen is rotating.

2. In a typewriter having a carriage, a rotatable shaft on the carriage, a platen carried by said shaft, and a turning member for the platen, a device for indicating the number of lines to be written on a page comprising a casing having a stationary backing plate secured to the carriage, a drum rotatable around and slidable with respect to the plate, a cover plate secured to the open end of the drum, a ring gear secured to the backing plate, a driving gear carried by the platen shaft, an idler gear journaled on the cover plate and normally out of mesh with the driving gear, the idler gear being in mesh with the ring gear, the idler gear being adapted to be moved into engagement with the driving gear by sliding the drum over the backing plate whereby rotary movement is imparted to the drum when the platen shaft is rotated, detent means associated with the drum and backing plate for maintaining the idler gear in engagement with the driving gear, means for releasing the detent means when the drum has been rotated to a predetermined position with respect to the backing plate, and spring means bearing against the cover plate to move the idler gear out of engagement with the driving gear upon release of the detent means.
